DESIGN FOR A FINGER RING

Henry J. Jung, Milwaukee, Wis.

Application January 26, 1942, Serial No. 105,427

Term of patent 14 years

To all whom it may concern:

Be it known that I, Henry J. Jung, a citizen of the United States, residing at Milwaukee, in the county of Milwaukee and State of Wisconsin, have invented a new, original, and ornamental Design for a Finger Ring, of which the following is a specification, reference being had to the accompanying drawing, forming part thereof.

In the drawing:

Fig. 1 is a top view of the finger ring with the hands clasped, showing my new design.

Fig. 2 is a side view of the finger ring with the hands clasped;

Fig. 3 is a top view of the finger ring with the hands unclasped; and

Fig. 4 is a side view of the finger ring with the hands unclasped.

The essential feature of my design resides in the specific configuration of the hand and wrist elements of the ring.

I claim:

The ornamental design for a finger ring, as shown and described.

HENRY J. JUNG.
